UNITED STATES PATENT OFFICE

2,145,910

CIGARETTE HOLDER

Henry Alpen, Milwaukee, Wis.

Application February 23, 1938, Serial No. 191,916

1 Claim. (Cl. 131—51)

This invention relates to an improvement in cigarette holders and aims to provide a device of this character which will not become soiled and unsanitary, which facilitates the smoking of a cigarette and which will not stain the fingers of the smoker.

In accordance with the present invention the holder is preferably combined with an ordinary pencil equipped with a clip of the type designed to releasably secure it in a pocket and is so constituted as to enable the clip to be conveniently used for its ordinary purpose and also for use in holding a cigarette. The device makes it practical for the smoker to write in between inhalations of the smoke without depositing the cigarette on an ash tray or other available support and picking it up each time it is used.

Another object of the invention is to provide a device of this character which is extremely simple in its construction, susceptible of convenient and graceful use, and adapted for economical manufacture and this in quantities.

Other objects and advantages reside in certain novel features of the construction, arrangement and combination of parts which will be hereinafter more fully described and particularly pointed out in the appended claim, reference being had to the accompanying drawing forming a part of this specification, and in which:

Figure 1 is a perspective view illustrating the manner of use of the device;

Figure 2 is a view in side elevation showing the invention as positioned when holding a cigarette;

Figure 3 is a fragmentary view in end elevation of the structure shown in Figure 1;

Figure 4 is a fragmentary view in side elevation looking at the opposite side of the structure from that viewed in Figure 2;

Figure 5 is a view similar to Figure 4 but showing the device when positioned to adapt the pencil to be supported in the usual manner in a pocket; and

Figure 6 is a plan view of the structure when positioned for holding the cigarette.

Referring to the drawing, the numeral 10 designates the pencil which may be of any conventional construction and which is equipped with a clip designated generally at 11. The clip 11 has the usual curved clamping members 12 which 50 slidably embrace the pencil and are frictionally engaged therewith at any point along its length. The clip has a resilient gripping finger 13 biased by virtue of its inherent resiliency into frictional engagement with the pencil and designed to slip 55 over the front wall of a vest pocket or the like in the usual way.

Integral with the body of the clip and extending in the opposite direction therefrom from the gripping finger 13 is a clamping member or holding member designated generally at 14. The

holding member 14 has a laterally extending curved cigarette engaging portion 15 which is dimensioned, proportioned, and disposed to overlie the rubber or eraser 16 usually provided at one end of the pencil when the clip is appropriately 5 positioned. The eraser 16, when one is provided, or the adjacent end of the pencil if not equipped with an eraser, affords a seat against which a cigarette C is adapted to engage. As shown in the drawing, the clip 11 may be adjusted to 10 cause its cigarette engaging portion 15 to engage and hold the cigarette against its seat. The pencil then provides a staff or handle which may be grasped in the hand of the smoker in the manner illustrated in Figure 1.

The cigarette engaging portion 15 is of ring-like form in that it has an opening 17 which provides for the adjustment of the clip to the position shown in Figure 5 and hence its capacity for normal use in holding the pencil in the pocket. 20

With the construction described the smoking of the cigarette is facilitated and moreover, the construction is such that it will not become soiled or stained, that is to say, it does not require the use of a cleaner since deposit of saliva or tobacco juice on any portion thereof is precluded. The smoker grasping the shank of the pencil will not have his fingers soiled or stained and it is entirely practical to write with the pencil in between inhalations of the smoke of the cigarette. The 30 tobacco user may thus enjoy the smoke and at the same time without the necessity of periodically laying his pencil down and picking it up.

While I have shown and described one construction in which the invention may be advantageously embodied, it is to be understood that the construction shown has been selected merely for the purpose of illustration or example and that various changes in the size, shape and arrangement of the parts may be made without departing from the spirit of the invention or the scope of the subjoined claim.

The invention claimed is:

A cigarette holder of the character described comprising a staff, a clip having a curved portion 45 in clamping engagement with the staff and slideable therealong, one end of the staff constituting a seat for a cigarette positioned transversely of the staff and with its axis substantially intersecting the axis of the staff, and a cigarette holding member interconnected with the clip and having laterally extending cigarette engaging spaced portions curved in a plane perpendicular to the plane of curvature of the clip and adapted to coact with the seat for securing a cigarette in 50 place thereon and adapted to be adjusted in surrounding relation about the staff in any longitudinal position thereof on the staff.
